UNITED STATES PATENT OFFICE

151,717

DESIGN FOR A NECKTIE OR THE LIKE

Walter F. Rothe, Washington, D. C.

Application May 21, 1947, Serial No. 139,181

Term of patent 14 years

(Cl. D3—16)

To all whom it may concern:

Be it known that I, Walter F. Rothe, a citizen of the United States of America, residing in Washington, District of Columbia, have invented a new, original, and ornamental Design for a Necktie or the like, of which the following is a specification, reference being had to the accompanying drawing, forming part thereof.

I claim:

The ornamental design for a necktie or the like, substantially as shown.

WALTER F. ROTHE.
